United States Patent Office.

ALBIN WARTH, OF STAPLETON, NEW YORK.

Letters Patent No. 105,613, dated July 19, 1870.

IMPROVEMENT IN BUNGS.

The Schedule referred to in these Letters Patent and making part of the same.

To all whom it may concern:

Be it known that I, ALBIN WARTH, of Stapleton, in the county of Richmond and State of New York, have invented a new and improved Tap and Bung combined; and I do hereby declare that the following is a full, clear, and exact description thereof, which will enable others skilled in the art to make and use the same, reference being had to the accompanying drawing forming part of this specification, in which drawing—

Figure 1 represents a central section of this invention.

Figure 2 is an inside view of the same.

Similar letters indicate corresponding parts.

This invention relates to that class of devices wherein the bungs and taps of vessels are combined; and

It consists in the combination and arrangement of certain parts, all of which will hereinafter be described.

In the drawing—

The letter A designates a bung, to the inner face of which is secured a tap, composed of a valve, a, which is pressed up, by means of a spring, b, against a seat, c, formed on the inner face of a plate, d.

From the inner surface of this plate extends an open tube, e, which incloses the spring b, and the seat c is bored out, to receive the spout f, which extends into a hole bored through the center of the bung.

The plate d is fastened to the bung by a flange-ring, g, and by screws, the joint between it and said bung being made tight by a packing-piece, h, (see fig. 1,) or in any desirable manner.

The spout f is, by preference, made in two parts, the outer part, i, being made in the form of an elbow and removable, so that the same can be withdrawn from the bung whenever it may be desirable.

When the bung is driven home in the bung-hole of a barrel or cask, said barrel or cask is hermetically closed, and it can be transported to any distance with perfect safety.

When it is desired to draw off some of its contents, the barrel or cask is turned so as to bring the bung in a horizontal or downwardly-inclined position, the elbow i is inserted, and, by forcing the valve a back against the action of its spring, the liquid contained in the barrel or cask is free to discharge.

It is obvious that the elbow i may be made to extend to any desired distance beyond the bung, so as to carry the liquid clear of the cask or barrel.

By these means a bung is obtained which is very cheap in its construction, costing less than one-twentieth of an ordinary tap, and which allows of tapping its cask or barrel with ease and convenience.

I am aware of the patent granted to Thomas Winder, January 26, 1869, No. 86,196; such I do not claim; but

What I claim as new, and desire to secure by Letters Patent, is—

The valve a, spring b, seat c, plate d, tube e, spout f, with the packing-piece h, interposed within the joint between the flanged ring g and the bung, the whole constructed and arranged as herein shown and described.

This specification signed by me this 23d day of May, 1870.

ALBIN WARTH.
